UNITED STATES PATENT OFFICE.

ROBERT B. SMITH, OF STOUGHTON, MASSACHUSETTS, ASSIGNEE TO UNITED SHOE MACHINERY COMPANY, OF PATERSON, NEW JERSEY, A CORPORATION OF NEW JERSEY.

EYELETING-MACHINE.

1,163,699.

Specification of Letters Patent. Patented Dec. 14, 1915.

Application filed June 28, 1910. Serial No. 569,282.

To all whom it may concern:

Be it known that I, ROBERT B. SMITH, a citizen of the United States, residing at Stoughton, in the county of Norfolk and 5 State of Massachusetts, have invented certain Improvements in Eyeleting-Machines, of which the following description, in connection with the accompanying drawings, is a specification, like reference characters on 10 the drawings indicating like parts in the several figures.

This invention relates to machines for setting fasteners, such, for example, as eyelets and the like, and more particularly to machines for handling and operating upon fasteners which are non-circular in shape.

It is frequently necessary to set fasteners which are elongated and difficulty has been experienced in handling these fasteners and 15 delivering them from the magazine to the raceway of an automatic machine.

The general object of the invention is to provide a machine for supplying and setting such elongated fasteners or fasteners 20 having more than one barrel, or single fasteners disposed with their barrels side by side.

The machine illustrated in the drawings is particularly adapted to handle fasteners 25 of the type known as "twin eyelets." These fasteners generally consist of two barrels similar to those of ordinary eyelets struck out from a single elongated flange.

Heretofore it has been customary to supply twin eyelets by hand to the setting dies in which they were to be clenched. This 30 was partly due to the difficulties referred to above and partly to the fact that no suitable means was known for supplying such eyelets from a raceway to a plurality of dies such as are necessary for effecting the setting of the eyelet.

An important feature of the present invention consists in a construction whereby 45 fasteners of the character described, or two single fasteners at a time, may be supplied from a raceway to a plurality of setting dies properly positioned to coöperate to set the fastener delivered thereto.

One preferred embodiment of the invention 50 includes a structure having a plurality of setting dies and a corresponding plurality of upsetting dies, the said dies being arranged in pairs, each pair consisting of a

setting die and a coöoperating upsetting die. 55 In the machine herein shown such pair comprising a setting die and an upsetting die is arranged in front of another similar pair and the raceway is positioned in line with the setting dies at the rear thereof and may 60 reciprocate along the line mentioned.

The double barreled fasteners lying longitudinally in the raceway as heretofore described, the fastener at the foremost end of the raceway will, when the raceway is 65 brought forward, be presented to the dies with the barrels in proper relation to the said dies to be operated upon thereby. A plurality of spindles mounted within the 70 setting dies, one for each barrel of the fastener, enter the fastener and remove it from the raceway as the latter is retracted.

While I have illustrated a machine for handling twin or double barreled fasteners, it should be understood that my invention is 75 not limited to the handling of fasteners with two barrels but may be successfully embodied, in machines which will handle fasteners with any desired number of barrels, which may be designated broadly as multiple 80 fasteners.

The spindles heretofore referred to for entering the barrels of the fastener and removing the latter from the raceway are 85 preferably mounted upon a common base actuated by a single actuating means, such as a spring. This insures that the spindle shall move simultaneously and thus shall enter the barrels of the fastener without difficulty.

Another feature of my invention comprises the provision, in a machine having a raceway for supplying or delivering fasteners, of improved means for retaining the fasteners in the raceway until it is desired 95 to remove one or more for insertion in the work. I preferably effect the desired result by means of a yielding spring latch lying above the endmost fastener in the raceway and having its end turned downwardly so 100 as normally to lie in front of said fastener. Such a device will yield to allow the ready removal of one or more fasteners when desired and immediately return to position to retain the remaining fasteners in the race- 105 way.

Other features of the invention will appear more fully in the following description

and will be pointed out in the appended claims.

In the drawings.—Figure 1 is a side elevation, partly in section, of an eyeleting machine embodying the features of my invention: Fig. 2 is a perspective view of a "twin eyelet" of the type adapted to be handled and set by the illustrated machine: Fig. 3 is a detail, partly in section, showing the arrangement of the ports in the magazine: Fig. 4 is a detail plan view of the forward end of the raceway: and Fig. 5 is a section on the line 5—5 of Fig. 4.

Referring to the drawings, 2 designates a base or suitable support upon which the frame 3 of the machine is mounted. The frame 3 is formed with a forwardly projecting upper portion 4 in the end of which are mounted the upsetting dies 6 for upsetting or clenching the eyelet barrels on the work.

6, 6 represent two upsetting dies mounted within the head 7 of a holder 8. The said holder 8 is secured in a suitably formed aperture in the end of the frame 4 by means of a set screw 9 and is stationary during the operation of the machine.

A plunger 10 is mounted to reciprocate vertically in a guideway 11 formed in the lower part of the frame of the machine, the axis of the said plunger coinciding with that of the holder 8. The plunger 10 is bored out as shown at 12 to receive and hold rigidly a die holder 13 in which are mounted setting dies 14, 14. Each of the setting dies is centrally drilled to allow the passage of a spindle 15. The die holder 13 is also drilled in line with the holes drilled in the setting dies so that the spindles 15 loosely pass through both the setting dies and their holder. The spindles 15 are both rigidly mounted at their lower ends in a button 16 which is freely slideable vertically within the recess 12 below the die holder 13. Within said recess is also located a spring 17 which normally presses the button 16 and the spindles carried thereby into their uppermost position, as shown in Fig. 1. The upsetting die holder 8 is mounted so that the upsetting dies 6, 6 lie one in front of the other, or, in other words, the said dies lie in a line extending from the front toward the rear of the machine. The setting dies 14, 14 are mounted to register respectively with their corresponding upsetting dies 6, 6 so that when a fastener, such as that illustrated in Fig. 2, is placed upon the lower or setting dies and the latter are moved toward the upsetting dies 6, the said upsetting dies will upset or clinch the ends 19 of the barrels of the fastener 18.

The mechanism for imparting a reciprocating movement to the plunger 10 is connected to the lower end thereof and may be of the same character and construction as

that illustrated in U. S. Letters Patent No. 898,729, granted September 15, 1908, to J. F. Davey.

In order to supply the fasteners 18 to the sets a magazine 20 for holding the fasteners and a raceway 21 for receiving them from the magazine and delivering them to the dies are provided. Within the magazine is an agitator 26 which oscillates and keeps the fasteners constantly moving. The magazine and raceway are mounted to reciprocate in the manner disclosed in the U. S. Patent above referred to. In order to effect separation of eyelets or fasteners in the magazine and permit their delivery therefrom to the raceway, ports 22 are provided in a portion of the periphery of the magazine. These ports are separated from each other by studs 23 which are cylindrical in form and are so spaced that the fasteners 18 can only pass lengthwise therebetween one at a time and with the barrels of the fastener upward. By reason of the cylindrical formation of the studs 23 the fasteners, while passing between the studs, are free to turn either upwardly or downwardly to bring their longitudinal axis into alignment with their subsequent direction of movement in the raceway 21. Any danger of blocking or choking of the ports or of the raceway is thus eliminated and a sufficient number of eyelets is delivered to the raceway to supply the needs of the machine. An inspection of Fig. 3 will show that in passing through the ports 22 of the magazine the eyelets can turn in either direction. This facilitates their entrance into, and proper arrangement within, the raceway.

The raceway is inclined downwardly and forwardly as illustrated in Fig. 1 and when in its delivering position intersects the axis of the rearmost dies and terminates substantially in line with the axis of the foremost dies. At the forward and lower end of the raceway a spring latch or detent 24 is mounted by means of a screw 27, or other suitable securing means. The forward end of the latch is deflected toward the center of the raceway as shown in Fig. 4 so as to lie above the endmost fastener in the raceway. The tip of the latch 24 is turned downwardly as shown at 25, the downwardly turned portion lying in front of the foremost fastener in the raceway, as clearly illustrated in Fig. 5. The latch 24 normally retains the supply of eyelets in the raceway but will yield to allow the removal of an eyelet by the spindles 15 when desired, immediately moving back into position in front of the next preceding eyelet in the raceway.

By constructing the latch so that it shall lie above, and extend down in front of, the eyelet which it engages in the raceway, an important advantage is secured in handling eyelets having an elongated outline inas-

much as it is necessary that such eyelets be presented to the sets in proper angular position with relation thereto. The latches heretofore used in automatic eyeletting machines engage the side of the eyelet and have a tendency to rotate the same as it is taken from the raceway. This is immaterial when circular fasteners, such as round eyelets, are being used but becomes a source of difficulty when an elongated or double barreled fastener is to be handled. With my improved device, the ends of the spindles 15 may, after passing through the barrels of the fastener, engage the latch and lift it slightly out of engagement with the fastener so that there is no tendency whatever to rotate the fastener as it is taken from the raceway and it is therefore easy to position the fastener properly and accurately upon the setting dies.

In the operation of the machine the agitator 26 keeps the fasteners in the magazine in constant movement and a sufficient number of them is delivered through the ports 22 always to maintain a supply in the raceway. As the plunger 10 is moved upwardly, the spindles 15 enter the barrels of the foremost eyelet in the raceway. The raceway is then moved rearwardly and the eyelet which is held upon the spindles 15 is disengaged from the raceway, the latch 24 immediately dropping down in front of the next fastener and preventing its escape. The plunger continues to move upwardly and the fastener carried by the setting dies 14 mounted upon said plunger is inserted in the work and upset or clenched against the upsetting dies 6, the downwardly projecting portions of which depress the spindles 15 against the tension of the spring 17. In the return of the plunger to its lowermost position the raceway is again moved forwardly in order to bring another fastener into position to be received upon the spindles of the setting dies in the next operation of the machine. It should be understood that the number of setting dies 14 and of the corresponding upsetting dies 6 is not limited to two but is only determined by the number 50 of barrels 19 upon the fastener to be handled by the machine.

Throughout this specification and in the following claims I use the term "setting die" to refer to that die which receives the fastener from the raceway, and the term "upsetting die" to refer to the coöperating die which upsets or clenches the barrel of the fastener upon the work. I also use the term "pair" to define a setting die and its coöperating upsetting die. For example, a setting die 14 and its coöperating upsetting die 6 form a "pair" in the sense in which that term is to be understood. The line in which the raceway 21 reciprocates extends 65 from the front toward the rear of the ma-

chine and is coincident with the plane containing the setting dies 14 and the upsetting dies 6, that is to say, the raceway is arranged to reciprocate in the direction of the line joining the dies 14 which receive the fastener from the raceway.

Having thus fully described my invention, what I claim as new and desire to secure by Letters Patent of the United States is:—

1. A machine for setting fasteners having, 75 in combination, a plurality of setting dies, a corresponding plurality of oppositely disposed upsetting dies, and means for successively bringing fasteners into alinement with and between all the dies, said means 80 comprising a raceway movable to and from a delivering position in which it intersects the axis of one setting die and terminates substantially in the axis of an adjacent die.

2. A machine for setting fasteners, comprising setting dies, a single raceway for supplying fasteners thereto, and means for reciprocating said raceway in line with said dies.

3. A machine for setting fasteners, having, 90 in combination, parallel setting dies, a single raceway for supplying fasteners to said parallel dies, and means for reciprocating said raceway in the plane of the axis of said dies.

4. A machine for setting double barreled 95 fasteners comprising setting dies arranged one in front of another, and means for delivering a fastener to said dies from the rear thereof.

5. A machine for setting fasteners comprising a plurality of setting dies each provided with a center spindle and means for delivering a double tubular fastener to said setting dies in a predetermined angular relation thereto.

6. A machine for setting eyelets comprising a plurality of setting dies and means for delivering successively single elongated fasteners to said plurality of setting dies with the major axes of said fasteners in a line 110 joining said dies.

7. A machine for setting double barreled eyelets comprising a pair of setting dies each provided with a center spindle, an integral holder for said pair of dies, and a 115 raceway for delivering a double barreled eyelet to the setting dies in such position that the barrels of the eyelet may be threaded simultaneously upon the spindles of the dies.

8. A machine for setting eyelets having a 120 tool comprising a pair of setting dies disposed side by side, a raceway arranged to extend in the plane of and above both setting dies so that two eyelet barrels may be brought simultaneously into alinement with the dies of the tool, and a coöperating tool comprising a pair of upsetting dies.

9. A machine for setting eyelets having, 125 in combination, a tool comprising an integral holder with a pair of setting dies set 130

therein, the dies being provided with center spindles disposed side by side, a raceway movable in the plane of the spindles so that two eyelet barrels may be brought into alignment with the spindles of the tool, and a coöperating tool comprising a pair of upsetting dies.

10. A machine for setting fasteners having double barrels, comprising a raceway for delivering fasteners, means to retain a fastener in position at the end of the raceway, setting dies and means arranged to simultaneously enter both barrels of the endmost fastener in the raceway to withdraw said 15 fastener from the raceway.

11. A machine for setting fasteners having double barrels, comprising means for delivering fasteners, setting dies, spindles mounted in said dies and a common spring for 20 said spindles.

12. An eyeleting machine having, in combination, a setting die provided with a center spindle, an eyelet supplying raceway having a yielding detent at its delivery end constructed and arranged with a flat body portion extending in alignment with and above

the eyelet barrels, and means for moving the setting dies and spindle toward the raceway whereby the spindle is passed through an eyelet in the raceway, engaging and raising 30 the detent for releasing the endmost eyelet.

13. A machine for setting tubular fasteners having, in combination, upsetting dies, setting dies located side by side and each having a setting spindle, and a common 35 spring for holding said spindles protracted.

14. A machine for setting tubular fasteners with two barrels, having in combination, a frame, oppositely disposed pairs of setting dies mounted therein, and a holder of one 40 pair of dies comprising a shank having an enlarged head formed thereon and parallel bores in said head for the reception of separate setting dies.

In testimony whereof I have signed my 45 name to this specification in the presence of two subscribing witnesses.

ROBERT B. SMITH.
